(57) **CLAIM**

The ornamental design for a guide vane for a vertical axis wind turbine, as shown and described.

DESCRIPTION

FIG. 1 is a front-left perspective view of a guide vane for a vertical axis wind turbine showing my new design;

FIG. 2 is a front-right perspective view of the guide vane for a vertical axis wind turbine;

FIG. 3 is a rear view of the guide vane for a vertical axis wind turbine;

FIG. 4 is a front view of the guide vane for a vertical axis wind turbine;

FIG. 5 is a right side view of the guide vane for a vertical axis wind turbine;

FIG. 6 is a left side view of the guide vane for a vertical axis wind turbine;

FIG. 7 is a top view of the guide vane for a vertical axis wind turbine; and,

FIG. 8 is a bottom view of the guide vane for a vertical axis wind turbine.

The broken lines shown depict the portions of the guide vane for a vertical axis wind turbine that form no part of the claimed design.
